REVERSIBLE STAND

Samuel Rappaport, Toledo, Ohio

Application November 8, 1954, Serial No. 32,997

Term of patent 14 years

(Cl. D33—14)

FIG. 1

FIG. 3

Fig. 1 is a side elevational view of a reversible stand embodying my new design, showing the stand in position for supporting a can or the like;

Fig. 2 is a plan view of the stand; and

Fig. 3 is a side elevational view of the stand taken at a 45° angle from that shown in Fig. 1, showing the stand in position for supporting a tray or the like.

The fragmentary broken line showings in Figs. 1 and 3, respectively, are for illustrative purposes only.

I claim:

The ornamental design for a reversible stand, as shown and described.
